[57] CLAIM

The ornamental design for a combined package of bottles with sleeve and shrinkable wrap.

DESCRIPTION

FIG. 1 is a perspective view of a combined package of bottles with sleeve and shrinkable wrap showing our new design;

FIG. 2 is a front elevational view thereof with the rear elevational view being the same;

FIG. 3 is a top plan view thereof;

FIG. 4 is a left side elevational view thereof with the opposite end view being the same; and,

FIG. 5 is a bottom plan view thereof.
